The ornamental design for a valve cover with diamond pattern, as shown and described.

DESCRIPTION

U.S. application Ser. No. 29/577,873 filed on the same date as the present application, entitled "Valve Cover," is incorporated herein by reference in its entirety.

FIG. 1 is a right top perspective view of a valve cover with diamond pattern in accordance with our new design;

FIG. 2 is a top plan view thereof;

FIG. 3 is a front elevation thereof;

FIG. 4 is a rear elevation view thereof;

FIG. 5 is a left side elevation view thereof, the right side elevation view is a mirror image thereof;

FIG. 6 is a right top perspective view thereof and shown attached to a base; and,

FIG. 7 is a right top perspective view of FIG. 7 and shown attached to a respirator.

The broken line showing of the base in FIGS. 6-7 and the respirator in FIG. 7 depict environment and form no part of the claimed design. All other broken lines depict portions of the valve cover with diamond pattern that form no part of the claimed design.
